Gottfried August Nebeling.

UNITED STATES PATENT OFFICE.

GOTTFRIED AUGUST NEBELING, OF REMSCHEID, GERMANY.

MEANS FOR RENDERING GROOVED-TILE ROOFS WEATHERPROOF.

SPECIFICATION forming part of Letters Patent No. 670,723, dated March 26, 1901.

Application filed December 11, 1900. Serial No. 39,533. (No model.)

To all whom it may concern:

Be it known that I, GOTTFRIED AUGUST NEBELING, a subject of the King of Prussia, Emperor of Germany, residing at Remscheid, in the Kingdom of Prussia, German Empire, have invented a new and useful Improvement in Means for Rendering Grooved-Tile Roofs Weatherproof, of which the following is a specification.

10 The present invention relates to an improved means for rendering grooved-tile roofing weatherproof. Not only is the roof thus made absolutely proof against all atmospheric precipitations, but any individual tile may be readily removed and the process of weatherproof tiling greatly facilitated.

15 The essential feature of the invention consists in the employment of a sheet of pasteboard, oiled paper, cloth, or the like as underlayer for each tile to rest upon. One edge of such layer of waterproof material is connected to a lateral bent metal strip or ridge-piece of the shape of an inverted gutter and adapted to fit into the groove of the tile. The opposite edge of the sheet is folded over the rib or ridge of the tile.

20 In the accompanying drawings, Figure 1 shows a sheet of pasteboard or other material *b* with metal strip *c* secured at one side. Fig. 2 is a detail view drawn to a larger scale, showing a cross-section of the metal strip and the manner in which the sheet is secured to it. Fig. 3 is a cross-section of a roofing-tile with waterproof layer in position below, portions 25 of the adjacent tiles being shown at either side to illustrate the method of setting them together. Fig. 4 is a plan view of a portion of a tiled roof, drawn to a smaller scale, the surface of the tiles, which may be of any design, being here shown flat. Fig. 5 is a longitudinal section of the roof, taken on the line *xx* of Fig. 4. Fig. 6 is a sectional detail view showing a manner in which the tiles may be firmly connected with the roofing-lath.

30 The size of the sheet *b* taken for each tile *a* must be such that at each end it projects somewhat beyond the metal strip *c* fastened to it, while in breadth it must be so much greater than the breadth of the tile itself that 35 when the metal strip is laid in the groove *g* the opposite edge of the sheet can be turned

over the rib or ridge *f*. In laying the tiles the groove *g* fits over the rib *f*, Fig. 3, and the metal strip *c* of the adjacent tile thus covers the edge of the sheet turned over, as described, so that the latter is securely held by the metal strip, which possesses some degree of resilience. The end of the sheet projecting beyond the metal strip lies on the roofing-lath *l*, Figs. 4 and 5, and can in front of the lug *m* of the tile be laid around the lath. The lower end of the sheet, on the other hand, forms the intermediate layer at the foot of the tile, between the latter and the head of the adjacent tile of the vertical row, and is pushed in according to the precise construction of the tiles and the manner in which they here join. Thus both at the sides as also at top and bottom of the tile a perfect joint is formed by means of the sheet, whereby rain and snow, even when accompanied by high wind, cannot penetrate the roof. The weatherproof character of the roof is also maintained even when the tiles are damaged, as through fractures or the like, since the sheet stops all moisture trickling through and allows it to run off. When it is required to lay a new tile, the damaged one can be readily removed and the new one set in its place, either in conjunction with the old or with a new sheet of waterproof material. Since the sheet is firmly grasped by the resilient metal strip on the one side and by being turned over on the other side is at once held fast, being also stretched to a certain extent, tiling can go on rapidly and without difficulty, the laths at the same time affording a safe foothold for the tiler.

35 In Fig. 6 I have shown a means by which the tiles can be firmly connected with the roofing-lath *l*, which consists of a metallic clamp *r*, such as tin or sheet-iron, which engages said tile and said lath, holding the same firmly together.

Having thus described my invention, what I claim as new, and desire to secure by Letters Patent, is—

40 Means for rendering grooved-tile roofs weatherproof, comprising a sheet of waterproof material lying under the tile and a bent metal strip *c* secured to one edge of said sheet and fitting unto the lateral groove *g* of the

tile, the opposite edge of said sheet being turned over the ridge *f* at the other side of the tile, in such manner that when the adjacent tile is laid, the said edge of the sheet is securely held by the metal strip *c* of such tile, substantially as described.

In testimony that I claim the foregoing as

my invention I have signed my name in presence of two subscribing witnesses.

GOTTFRIED AUGUST NEBELING.
